UNITED STATES PATENT OFFICE.

RAY W. ARMS, OF CHICAGO, ILLINOIS, ASSIGNOR TO ROBERTS & SCHAEFER COMPANY, OF CHICAGO, ILLINOIS, A CORPORATION OF ILLINOIS.

DUST-COLLECTING SYSTEM FOR DRY-CLEANING TABLES.

Application filed January 9, 1926. Serial No. 80,138.

My invention relates to dust collecting systems and apparatus for dry cleaning or air separating tables and the like, and has for one object to permit the withdrawal from the 5 coal or other material being cleaned of a minimum percentage of the dust. Other objects are to provide a dust collecting system and apparatus wherein only enough dust laden air is withdrawn to prevent the 10 charge of dust into the atmosphere of the room containing the dry cleaning apparatus.

In connection with some dust collecting apparatuses which have been suggested for this general purpose, an effort has been made to withdraw all the dust from with the material 15 being treated, in some instances this means that as much as twenty percent by weight of the material fed to the dry cleaning tables is drawn off with the dust laden air. This is 20 undesirable both because of the large volume of dust laden air that must be handled and cleaned and because of the serious loss in weight of the coal that otherwise might be profitably used.

25 In my apparatus and by my method where I draw off just enough excess air from above the air cleaning table to prevent the discharge of air into the room from the table, and where no effort is made to force off any dust beyond 30 that in the air as a direct result of the air cleaning, only about two percent by weight of the material comes off as dust.

My invention is illustrated more or less diagrammatically in the accompanying drawings, wherein—

35 Figure 1 is a plan view with parts omitted and parts broken away of a dry cleaning table to which my invention has been applied;

Figure 2 is a side elevation with parts broken away of the apparatus illustrated in Figure 1; and

Figure 3 is an end view.

Like parts are indicated by like characters throughout the specification and drawings.

40 A is a supporting frame upon which is mounted the table A¹ by means of the links A², reciprocated by an eccentric or crank which applies its power to the table through the connecting rod A³. A⁴ is an air pervious 45 deck carried by the table and adapted to support and guide the flowing sheet of material as it travels across the separating zone and as it is subjected to the separating action of the air column. A⁵ is a chimney through 50 which the air or gas which assists in the dry

cleaning process is fed and guided to the underside of the pervious deck, and A⁶ is a chute through which the coal or other material to be treated is fed to the deck. A⁷ is a discharge trough arranged about the discharge sides 60 of the table and adapted to catch the various parts of the separated sheet of material as it flows off the deck after treatment and to distribute the various products as desired 65 through the chutes A⁸.

B is an air hood which overlies the table and deck, and is connected or joined to the periphery of the table by the aprons B¹ which make a substantially air tight joint between the deck and the table without in any way interfering with the reciprocating of the table. Thus the only openings between the hood and the table are those through which the coal enters the treating zone and through which it leaves the table after treatment. The 70 hood has as shown a large widely extended area immediately above the table where the velocity of the air as it rises from the table is if anything reduced so as to provide a settling zone wherein any dust particles which 75 may have been thrown up from the material being treated will be given an opportunity to settle out from the air current and be returned to the sheet of material. Above this settling zone the hood tapers as at B² toward the discharge passage B³ which leads to any suitable form of air separator and air 80 exhausting apparatus. The volume of air drawn out through this passage is but slightly in excess of the volume of air fed through the 85 deck and is just sufficient to prevent the escape of dust laden air into the room in which the apparatus is located.

It will be evident that while I have shown in my drawings and described in my specification an operative form of my device still many changes in shape, operation and arrangement of parts may be made without departing materially from the spirit of my invention and I wish therefore that my drawings be regarded as in a sense diagrammatic.

The use and operation of my invention are as follows:

The hood which overhangs the table is connected to it everywhere except at the 105 points where the coal is fed to the table and at the point where coal is withdrawn or discharged from the table. It may or may not be connected to the coal chute or to the chutes which carry off the treated or separated prod-

uct. It can be connected by means of a flexible diaphragm or the like or mounted directly on these elements but the connection in any event is substantially air tight so that the 5 only connection between the air above the table under the hood and the outside air is through the coal supply chute and the discharge chute.

An air vent leads from the upper portion of 10 the hood to any suitable dust separating apparatus and means are provided to draw a current of air upwardly through the hood through such vent. The volume of air so withdrawn will be substantially the same as 15 the volume of air fed to the hood upwardly through the deck or table but the relative amounts will be so proportioned as to prevent the discharge of air from the hood or from between the hood and the table at any 20 points adjacent to the table so that there will be an ingoing air current travelling with the coal as it reaches the screen and an ingoing air stream travelling against the coal as it is discharged from the table. Thus all dust 25 laden air will be compelled to pass out through the vent or upper passage of the hood.

The hood is an expanding one and serves as 30 an air settling chamber above the deck so that a large proportion of the dust which may be raised above the sheet of material being treated by the floating air will have an opportunity to drop back into the bed and only a relatively small part of the dust will 35 find its way out through the conduit from the top of the hood. Experience shows that whereas if the dust laden air is forced and an effort is made to compel all of the dust to leave the coal as high as twenty percent by 40 weight will be withdrawn and must then be otherwise handled and whereas by the use of the expanding settling chamber hood together with a very gentle air current most of the dust returns to the coal and only something like two percent is carried off to be 45 separately treated.

It will be noted especially that the discharge pipe B³ is located over the feed end of the table which is, experience has shown, the 50 dustiest part of the table and it will also be noted especially that the bellows from the

hood down to the table comes over the chutes through which discharge of the coal and refuse takes place, thus insuring a current of make up air into the space above the table in a direction opposite to the outflow of material from the table and thus taking off from such material those light dust particles which might otherwise as the coal is further handled be blown off the building and make conditions 55 unsatisfactory. Any dust that goes on against this air current is dust just sufficiently adhering to the material to insure that it has good chances of getting clear out of the system and being shipped with the coal as it 60 should be.

I claim:

1. In a dry cleaning apparatus, a pervious reciprocating deck, means for feeding a flowing sheet of granular material thereacross, 70 means for passing a moving column of air upwardly thru the sheet, a hood located above the deck containing an air settling chamber bounded on its underside by the sheet of material and means for withdrawing air from said hood at a point above the settling chamber 75 and widely separated from the sheet of material, and a closure between the hood and the deck at all points about its periphery except the space thru which the sheet of material enters and is discharged from the deck, the hood being fixed in position independent of the movement of the deck.

2. In a dry cleaning apparatus, a pervious deck, means for feeding a flowing sheet of granular material thereacross, means for passing a moving column of air upwardly through the sheet, a hood located above the deck, means for withdrawing air from said hood, a flexible connection between the hood and the deck to limit the entrance of air between them, chutes through which material is discharged from the deck, the flexible connections overlying the chutes and so arranged as to insure a draft of air upwardly through 90 said chutes in a direction opposite to the flow of the material as it is discharged from the deck.

Signed at Chicago, county of Cook and State of Illinois, this 14th day of December, 1925.

RAY W. ARMS.
